UNITED STATES PATENT OFFICE

MATTHEW F. BAYER, OF KENOSHA, WISCONSIN, ASSIGNOR TO SIMMONS COMPANY, OF NEW YORK, N. Y., A CORPORATION OF DELAWARE

BED

Application filed June 22, 1925. Serial No. 38,611.

This invention relates to improvements in bed structures and more particularly to that type of bed known as a roller bed. Such beds are used to cut down the number of rooms necessary for a given requirement, by enabling the occupant of a room to use any room in the night-time as a bed-room, and in the day-time, by folding the bed, to render it easily rolled out of the way, into a closet or other space, to use that same room as a living room or for other purposes.

The principal object of this invention is to provide a safe and efficient light weight roller bed which may be folded into small compass with a minimum of effort.

Other objects and advantages of this invention will be apparent when reference is had to the following specification when considered in connection with the accompanying drawings which illustrate a selected embodiment thereof, in which

Fig. 1 is a perspective view showing my improved bed in the course of being folded or unfolded.

Fig. 2 is a side elevation showing the bed in position for use.

Fig. 3 is also a side elevation, but showing the bed in its folded position wherein it may be easily rolled away and stored.

Fig. 4 is a section on the line 4—4 of Fig. 3 and

Fig. 5 is a section on the line 5—5 of Fig. 2.

Referring now to the drawings, and particularly to Fig. 2, my improved bed includes a bed frame 1, a base 2, and end frames 3 and 4. The bed frame comprises side bars 5 and end rails 6 and 7, between which latter, the bed fabric 9 is stretched in the usual manner. The end rails 6 and 7 are mounted on suitable risers 8 secured to the ends of the side bars 5.

The end frame 3, having folding legs 10 is secured to one end of the bed frame and provides one of the supports therefor. Suitable casters may be provided in these legs to facilitate moving of the bed when it is in unfolded position. The base 2 comprises side frames 11 connected by cross members 12, 13 and 14, and is provided with easy-running casters 15. The top member 16 of each of

the side frames 11 is arched and of channel shape so as to provide guide-ways 17—17 to receive rollers 18—18 journaled on axially horizontal pins, which are fixed in the side bars 5. By means of the rollers 18—18 the bed frame 1 is thus pivotally and slidably connected to the base 2.

A U-shaped member, having upwardly extending arms 21—21, and an integral horizontal cross member 22, is pivotally connected at 23—23 to the base 2.

The upper ends of the arms 21—21 are pivotally connected to the side bars 5 at points 24—24 which are spaced a substantial distance from the rollers 18—18.

A plurality of springs 19 are tensioned between the cross member 20 of the bed frame and the cross member 13 of the base.

The end frame 4 is pivotally connected by pivots 26—26 to the posts 27—27 which are secured to the risers 8. Links 28—28 extend between pivots 29 on the sides of the end frame and pivots 30 on the extended ends 31 of the arms 21—21.

The aforementioned folding legs 10, are controlled by means of jointed toggle members comprising upper links 32—32, having their upper ends connected at 33—33 to the side bars 5 and having their lower ends connected to pivots 34—34 at the upper ends of somewhat longer links 35—35. The links 35 have their lower ends connected to the folding legs 10.

Buckling of the above described toggle members and consequent folding of the legs 10 is achieved by means of the rods 36—36, which are pivotally connected at one end to the pivots 34—34 of the toggle members, and at their other end are pivotally connected at 37—37 to the arms 21. The pivotal connection 37—37 is preferably located intermediate the pivot points 23 and 24 on the arms 21, at a point, which when the bed is folded, will give the necessary travel to the rod 36 to buckle the above described toggle members, and thereby obtain the desired folding action of the legs 10.

In operation, when the bed is to be folded from the position shown in Fig. 2 to the position shown in Fig. 3, the end of the bed

frame, away from the base, is raised by hand, the raising thereof being aided by means however, of the tension springs 19.

The bed frame 1 pivots on the rollers 18-18 in the guide ways 17-17 and on the pivots 24-24 in the arms 21-21, and as the frame is raised at its foot end, the pivots 24 are also raised in an arc described about the pivot points 23, thereby causing a general elevation of the entire bed frame so that 10 when it is folded to its vertical position (Fig. 3) the end frame 4 will be positioned within the base 2.

Clamps 40 are provided to securely hold the mattress and other bedding in place at 15 one end, and at the other end the end frame 4 serves that purpose when the bed is in its folded position, this being achieved through the medium of connecting links 28 and the extended ends 31 of the arms 21. As the bed 20 is folded, the extended ends 31, acting as lever arms pivot on the pivots 24-24 and pull the links 28-28 in such a manner that the frame 4 is folded on the pivots 26-26 25 until it assumes the position shown in Fig. 4, where it may be readily seen that it will form a receptacle and a holding member for pillows and other bedding, and also hold the mattress in position. The links 28 are 30 preferably curved as shown, so that the surface of the bed will be free from obstructions at the sides.

Lugs 41 on the bed frame engage stops 38 at the base to limit the movement of the bed 35 frame at that point and the travel of the rollers 18-18 is limited by end walls 39-39 of the guide-ways 17-17.

The bed frame is retained in folded position due to the fact that the center of gravity of the bed frame, when in folded position, is 40 located a substantial distance behind a vertical plane passing through the centers of the pivotal connections between it and the base. When in folded position the weight of the bed frame thus tends to cause the bed frame 45 to swing rearwardly on its pivotal connection with the base, but this tendency is overcome by means of the stop 38 on the base and lugs 41 on the frame.

Heretofore, with beds of this general type, 50 without some special arrangement, it has been difficult to apply counter-balancing or elevating springs of sufficient power to furnish the required assistance in balancing the extended portion of the structure during the folding operation. This has been due to the 55 fact that the base of the bed must necessarily be of quite small dimensions in order to permit the bed when folded to enter the doorway of the closet or compartment in which it is stored when not in actual use. Obviously, with a base of such small dimensions and of comparatively light weight, heavy construction being undesirable in a portable bed, 60 if springs of more than a certain power be

employed, any additional power will simply tend to lift the rear portion of the base from the ground, and will perform no useful lifting function as to the overhanging or extending portion of the bed.

Since such roller beds in practice have to be operated sometimes by persons possessed of a limited amount of strength, some effective counter-balancing means must be employed and, in most cases, this has been in the form of a very heavy counterweight, which, of course, makes the structure very heavy to move around, thus reducing the portability of the bed. Other inventors have proposed the use of extension arms which, when the bed is unfolded, may be projected either manually or automatically outwardly of the base so as to increase the effective dimensions of the base and permit the use of springs of sufficient power.

It will be manifest that with my arrangement, undesirable counterweights, or in the alternative, extension arms are not required. With my construction, the bed frame is so connected to the base that when the device is unfolded, in addition to the usual swinging movement of the bed frame on its base, there is in effect a longitudinal or sliding movement thereof which causes the bed frame to move a substantial distance inwardly of the base. Thus the base of the structure in effect has a relative movement outwardly and under the bed frame when the latter is unfolded, and the center of gravity of the entire structure, without the aid of a counterweight and without the aid of any foldable projections or extensions, is always maintained substantially within the area of the fixed base. Thus, springs of any desired power may be employed to balance the weight of the overhanging portion of the bed frame and parts carried thereby.

It will be seen also that I secure this very desirable result by use of a structure which has the additional feature that the danger of accidental folding of the device when extended, due to excess of weight being imposed near the head end of the bed frame, is entirely eliminated. This is due to the fact that the rollers 18 are positioned quite close to the head end of the bedstead and rearwardly of the upper link pivots and they are supported on the fixed upwardly curved track 17 so that in the folding operation the initial movement of the rollers is upward. The elevating springs, when in the position shown in Fig. 2, have practically no folding effect, as they have no substantial tendency to cause a depression of the head end of the bedstead. In such completely extended or unfolded position, with the arrangement shown, the weight of the bed frame is, in a sense, slightly unbalanced so that the foot end of the bed will be held solidly on the floor. This incomplete balancing of the structure in it-

self, largely eliminates any tendency towards collapsing or folding of the bed due to imposition of excess weight on the head end. However such unbalancing has no serious or detrimental effect in folding of the bed since when the bed is in its completely extended position, the operator is in the best possible position to exert an upward pull on the foot end of the bed. As soon as the foot end is elevated a few inches from the horizontal, the relative position of the springs and pivots changes so that during the remainder of the folding movement, the weight of the bed frame is properly balanced and no further considerable force is required to complete the folding of the structure.

I claim as my invention:

1. A bed comprising a bed frame and a base, an arm pivotally connected at one end to said base and at its other end, to said frame, legs pivotally mounted at one end of said bed frame, a toggle connection between said legs and frame, a link operatively connecting said toggle with said arm.

2. A bed comprising a bed frame provided with suitable mattress supporting means, a base having suitable casters secured thereto, a balancing spring connected between said bed frame and base, a pivot secured to said bed frame, a guide-way on said base for said pivot, an arm pivotally connected at one end to said base and at its other end to said bed frame, legs pivotally mounted at one end of said bed frame, a toggle connection between said legs and said bed frame, a link operatively connected between said toggle and said arm, an end frame pivotally mounted at the other end of said bed frame, a lever arm extending from the first mentioned arm and a link operatively connected between the last said end frame and lever arm.

3. A bed comprising a bed frame and a base, an arm pivotally connected at one end to said base and at its other end to said frame, legs pivotally mounted at one end of said frame, a toggle connection between said legs and bed frame, a rod pivotally connected at one end to said toggle, and at its other end to said arm at a point intermediate the base connection and frame connection thereof.

4. A bed comprising a bed frame and a base, an arm pivotally connected at one end to said base and at its other end to said bed frame, a folding frame pivotally connected to one end of said frame and a link pivotally connected at one end to said end frame and at its other end to an extension of said arm at a point spaced outwardly from its frame pivot, legs pivotally connected at the other end of said bed frame, a toggle connection between said legs and bed frame, a rod pivotally connected at one end to said toggle and at its other end to said arm at a point

intermediate the base connection and frame connection thereof.

5. In a roller bed structure, the combination of a rigid base of front to rear dimension small enough to permit said base to enter an ordinary doorway, a link having its lower end pivoted to said base, a bed frame pivoted to the upper end of said link, a balancing spring for assisting in folding of the bed frame and means for controlling the pivotal movement of said bed frame on said link when said arm rocks on its pivot, the link being arranged to swing the bed rearwardly of the base to cause the rear end of the bed to project substantially beyond the base when the bed is unfolded; said controlling means comprising a roller and a generally horizontal track one provided on the base and the other on the bed frame.

6. In a roller bed construction, the combination of a base of weight sufficient only for the required structural strength, a link having its lower end pivoted to the forward end of said base, a bed frame pivoted to the upper end of said link, a generally horizontal track in an elevated position on said base, a pivot mounted on said bed frame at a point rearwardly of the connection between the frame and the link and a substantial distance forward of the rear end of the frame and cooperating with said track to move the upper end of said link rearwardly when the bed is unfolded so as to maintain the center of gravity of the combined structure within the area of the base, and a balancing spring connected between said base and a point on said frame intermediate said pivots.

7. In a roller bed construction, the combination of a base, a link having its lower end pivoted to the forward end of said base, a bed frame pivoted to the upper end of said link, an upwardly arched generally horizontal track in an elevated position on said base, a pivot mounted on said bed frame at a point rearwardly of the connection between the frame and the link and a substantial distance forward of the rear end of the frame, and cooperating with said track and a balancing spring connected between said base and a point on said frame intermediate said pivots.

8. In a roller bed structure, the combination of a rigid base, of front to rear dimensions small enough to permit said base to enter an ordinary doorway, a link having its lower end pivoted to the front of said base, a bed frame normally when in upright position located within the area of the base and pivoted to the upper end of said link, a shifting pivotal connection between said base and a point on said bed frame rearwardly spaced from the upper pivot of said link and substantially spaced from the rear end of the frame for controlling swinging movement of the frame on the link pivot during the fold.

ing and unfolding operation, the arrangement being such that when the bed is extended, the upper link pivot is in a position considerably in the rear of the base pivot and the rear end of said frame projects a substantial distance 5 rearwardly of the base, and spring means tending to elevate the front end of the bed frame, when the bed is being folded, said shifting pivotal connection comprising a roller on the bed frame and an elevated generally horizontal track member on said base cooperating with said roller.

9. In a roller bed structure, the combination of a rigid base, of front to rear dimensions small enough to permit said base to enter an ordinary doorway, a link having its lower end pivoted to the front of said base, a bed frame normally when in upright position located within the area of the base and pivoted to the upper end of said link, a shifting pivotal connection between said base and a point on said bed frame rearwardly spaced from the upper pivot of said link and substantially spaced from the rear end of the frame for controlling swinging movement of the frame on the link pivot during the folding and unfolding operation, the arrangement being such that when the bed is extended, the upper link pivot is in a position considerably in the rear of the base pivot and the rear end of the said frame projects a substantial distance rearwardly of the base, and spring means tending to elevate the front end of the bed frame, when the bed is being folded, said spring being connected to said bed frame intermediate the upper link pivot point and the shifting pivotal point, said shifting pivotal connection comprising a roller on the bed frame and an elevated generally horizontal track member on said base base cooperating with said roller.

10. In a roller bed structure, the combination of a rigid base of weight not materially greater than is required for purposes of structural strength and rigidity and of front to rear dimensions small enough to permit said base to enter an ordinary closet doorway, a link having its lower end pivoted to the front of said base, a bed frame having its head or lower end of weight not materially greater than is required for purposes of structural strength and rigidity and normally, when in upright position, located within the area of the base, said frame being pivoted to the upper end of said link, a shifting pivotal connection between said base and said bed frame spaced rearwardly from said upper link pivot for controlling swinging movement of the frame on the link pivot during the folding and unfolding operation, the arrangement being such that when the bed is extended from vertical to horizontal position, the upper link pivot is moved rearwardly to a position considerably in the rear of the lower link pivot and the rear end of said frame is moved rearwardly so as to project a substantial distance rearwardly of the base, so that the center of gravity of the combined structure falls within the area of the base, and spring means tending to elevate the front end of the bed frame, when the bed is being folded, and powerful enough to adequately counterbalance the overhang of the bed when the latter is extended horizontally.

11. In a roller bed structure, the combination of a rigid base of weight not materially greater than is required for purposes of structural strength and rigidity, and of front to rear dimensions small enough to permit said base to enter an ordinary closet doorway, a link having its lower end pivoted to the front of said base, a bed frame having its head or lower end of weight not materially greater than is required for purposes of structural strength and rigidity and normally, when in upright position, located within the area of the base, said frame being pivoted to the upper end of said link, a shifting pivotal connection between said base and said bed frame spaced rearwardly from said upper link pivot for controlling swinging movement of the frame on the link pivot during the folding and unfolding operation, the arrangement being such that when the bed is extended from vertical to horizontal position, the upper link pivot is moved rearwardly to a position considerably in the rear of the lower link pivot and the rear end of said frame is moved rearwardly so as to project a substantial distance rearwardly of the base, so that the center of gravity of the combined structure falls within the area of the base, and spring means tending to elevate the front end of the bed frame, when the bed is being folded, and powerful enough to adequately counterbalance the overhang of the bed when the latter is extended horizontally.

12. In a roller bed structure, the combination of a rigid base of weight not materially greater than is required for purposes of structural strength and rigidity and of front to rear dimensions small enough to permit said base to enter an ordinary closet doorway, a link having its lower end pivoted to the front of said base, a bed frame having its head or lower end of weight not materially greater than is required for purposes of structural strength and rigidity and normally, when in upright position, located within the area of the base, said frame being pivoted to the upper end of said link, a shifting pivotal connection between said base and said bed frame spaced rearwardly from said upper link pivot for controlling swinging movement of the frame on the link pivot during the folding and unfolding operation, the arrangement being such that when the bed is extended from vertical to horizontal position, the upper link pivot is moved rearwardly to a position considerably in the rear of the lower link pivot and the rear end of said frame is moved rearwardly so as to project a substantial distance rearwardly of the base, so that the center of gravity of the combined structure falls within the area of the base, and spring means tending to elevate the front end of the bed frame, when the bed is being folded, and powerful enough to adequately counterbalance the overhang of the bed when the latter is extended horizontally, said shifting connection being so arranged that when commencing to fold the bed, downward movement of said connection is prevented, thereby stabilizing the structure in respect of loads applied to the head end of the bed.
